RACK INSERT FOR GOLF BAGS

Louis L. Konke, Los Angeles, Calif.

Application May 16, 1955, Serial No. 508,504

4 Claims. (Cl. 150—1.5)

This invention relates to a rack for supporting golf clubs and has as its primary object the provision of a golf club rack which is adapted to be mounted within a golf bag and then serve as a means for holding the handles of a multiple of golf clubs in separated spaced relation to each other while the clubs are carried in the bag and whereby interlocking of the club handles in the bag will be prevented and whereby withdrawing of a club from the bag will be facilitated.

Another object is to provide a rack of the above character which is so designed that it may be assembled apart from the bag and then be readily positioned within the bag and securely fastened in place therein.

Another object is to provide a golf club rack which is light in weight so as not to appreciably increase the weight of the bag to which it is applied which is strong and durable and which will withstand hard usage.

Another object is to provide a rack which may be marketed in knocked-down condition so as to effect economy in space during shipment and storage, yet which may be readily assembled and mounted in a golf bag by persons of ordinary skill.

A further object is to provide a rack embodying a pair of superimposed complementary apertured club receiving plates together with frame members whereby the plates are secured in suitable spaced relation to each other and be spaced from the upper and lower ends of the bag in which the rack is mounted.

A particular object of the invention is to provide a simple and adequate means for smoothly guiding the handles of golf clubs, on passing thereof through the apertures in the uppermost plate, downwardly through the apertures in the lowermost plate, and which is effective irrespective of whether the bag is positioned upright or horizontal, or at an inclination as when being carried.

A still further object is to provide a club rack for golf bags which is characterized by the embodiment of flexible and resilient guide-ways so as to be capable of yielding and bending under pressure whereby the load of the bag and its contents will be cushioned against the body of a person carrying the bag either across the back or over the hips thus easing the burden and rendering it more comfortable to carry.

With the foregoing objects in view together with such other objects and advantages as may subsequently appear, the invention resides in the parts and in the combination, construction and arrangement of parts hereinafter described and claimed, and as illustrated by way of example in the accompanying drawings in which:

Fig. 1 is a perspective view in transverse section of a golf bag showing the club supporting rack mounted therein;

Fig. 2 is a vertical sectional view of the rack partly in elevation;

Fig. 3 is a horizontal section and plan view taken on the line 3—3 of Fig. 2;

Fig. 4 is a detail in cross section partly in elevation as seen on the line 4—4 of Fig. 3; and

2

Fig. 5 is a detail in elevation as seen on the line 5—5 of Fig. 2.

Referring to the drawings more specifically A indicates generally a conventional golf bag, a vertical half of which is shown in Fig. 1, and B designates the golf club rack designed for positioning within the bag A.

The golf bag is here shown as comprising a flexible fabric tube 6 one end of which is closed by a relatively stiff bottom wall 7 and the other end of which is open and fitted at its margin 8 with a rigid metallic reinforcing ring 9 which serves to maintain the bag open at its upper end. The margin 8 extends at an inclination from the back portion of the bag to the front portion thereof as is common in golf bag construction.

The rack B embodies a pair of complementary rigid plates 10 and 11 the margins of which at least substantially conform to the contour of the inner periphery of the bag A, and which plates are formed with a plurality of circular golf club receiving apertures 12—13 respectively with the apertures of one plate registering or aligned with the apertures of the other plate. The plates 10—11 are designed to be spaced apart in the bag A with the upper plate 12 spaced below the open upper end of the bag and with the other plate spaced from the bottom wall 7 of the bag. As a means for supporting the plates in such spaced relation and in parallel relation to each other and to the bottom wall 7 and also to sustain the flexible tube 6 against longitudinal collapse a frame is provided which consists of a pair of parallel elongated and narrow posts 14 and 15 arranged at opposite ends of the plates 10—11 and to which the latter are rigidly attached by angle brackets 16 each having one arm thereof secured by a screw *a* to the plate and the other arm secured to the adjacent post by a screw *b*. The posts 14—15 are of rectangular cross section and are fitted into conforming notches *c* formed in the end margins of the plate which serve to stabilize the connection between the plates and posts as well as to position the outer faces of the posts flush with the margins of the plates. The posts 14—15 may be connected together at their lower ends by a base strip 19 which is secured to the posts as by staples *d* or similar fastenings and is adapted to seat on the bottom wall 7. However this strip 19 is not essential since the lower ends of the posts may seat directly on the bottom wall 7.

The post 14 is designed to extend adjacent the inner face of the rear wall portion of the bag from the base strip 19 or bottom wall 7 to adjacent the uppermost point of the inclined margin 8 of the bag beneath the ring 9 while the post 15 is designed to extend adjacent the inner face of the front wall portion of the bag from the base strip 19 or bottom wall 7 to adjacent the underside of the ring 9 at the lowermost portion of the inclined margin of the bag.

As a means for fastening the rack B within the bag A, the upper end portions of the posts 14—15 are connected to the contiguous portions of the bag by fasteners 17 here shown as comprising bolts *e* which pass through the posts and bag and are fitted with nuts *f* in the usual manner which bolt and nut assemblies afford a means whereby the rack may readily be engaged with and disengaged from the bag. A reinforcing strip or band *g* may be affixed to the bag where the fasteners 17 engage the latter.

A feature of the invention resides in forming the plates 10—11 with opposed elongated openings 18 for the reception of the putter club which is characterized by having a handle so shaped and dimensioned as not to be receivable in the circular apertures 12—13.

Means are provided for guiding the handles of golf clubs passed through the apertures 12 in the upper plate 10 to direct the handles to and through the apertures 13 in the lower plate 11. This means consists of a series of flexible and resilient rods 20 extending in paral-

lal relation to each other between the plates 10—11 with their ends engaged in holes formed in the plates to receive them. The rod receiving holes *h* in the uppermost plate 10 are dimensioned to slidably receive the rods 20 which in assembling the rods are passed longitudinally therethrough, while the holes *i* in the lower plate 11 are dimensioned to receive the lower ends of the rods 20 with a snug driving fit to securely hold the rods in place. The plates 10—11 are preferably formed of sheet metal while the rods 20 are preferably formed of wood such as dowel stock which in lengths required to span the space between the plates 10—11 are flexible and resilient. However it is manifest that the plates 10—11 may be formed of wood or plastic and that the rods 20 may be formed of metal or plastic.

The circular apertures 12—13 are dimensioned to permit the free passage therethrough of the handles of the golf club to be carried therein, while the guide-rods 20 are arranged around and aligned with the perimeters of the apertures with adjacent rods spaced apart a distance less than the diameters of the golf club handles so as to confine the handles between the series of rods leading between the margins of opposed apertures.

In this instance the rods are arranged in most part at 90° intervals around the circumferences of the apertures, and where the apertures are axially aligned transversely of the plates a single rod is disposed in the web *j* separating adjacent apertures so as to serve as a guide between both of such apertures.

Where the margins of outermost apertures lie close to the margins of the plates such that the walls of the tube 6 will serve as a guide the employment of a guide-rod 20 at such point may be dispensed with.

Manifestly the pieces of which the rack B is formed may be readily assembled and accordingly are adapted to be merchandised in a knocked-down condition.

The operation of the invention is apparent from the foregoing it being manifest that mounting of the assembled rack B in the golf bag A involves merely inserting the rack in the bag to its seated position therein and then securing it in place by application of the fastenings 17.

Mounting of golf clubs in the rack simply involves inserting the handle ends of the clubs through the apertures 12 in the upper or outer plate 10 and thrusting the clubs along the guideways formed by the rods 20 and through the apertures 13 in the lower or inner plate 13 to a seated position on the bottom wall 7 of the bag, as indicated at *k* in Fig. 2. A series of golf clubs may thus be mounted in the rack with each club independently supported so that a single club may be readily removed by withdrawing it longitudinally from the rack, which is effected without disturbing adjacent clubs.

Manifestly while carried in the rack the series of clubs will be supported by the plates 10—11 with their handles clear of each other irrespective of the normal position of the bag and with the assembly of clubs at least substantially surrounded by the outermost rods 20. These rods being flexible and resilient yield transversely under pressure applied at or near the mid-length thereof thus affording a spring or cushioning action which serves to afford comfort in carrying the bag which is fitted in the usual manner with shoulder straps (not shown) connected to the rear portion of the bag, and whereby the bag is carried either across the back or at the sides above the hips. This yielding characteristic of the rods further

minimizes breakage thereof on being subject to impact delivered to the side of the bag.

While a specific embodiment of the invention has been shown and described, the invention is not limited to the exact details of construction set forth, and the invention embraces such changes, modifications and equivalents of the parts and their formation and arrangement as come within the purview of the appended claims.

I claim:

10. In a club rack insert for golf bags, a pair of complementary plates formed with corresponding arrangements of club supporting apertures, a pair of elongated narrow posts between which said plates are interposed and arranged in spaced parallel relation to each other, means rigidly fastening said plates to said posts, and a series of parallel rods extending between said plates and connected at their ends thereto, there being a plurality of said rods leading from the margin of each of the apertures in said plates.
15. In a club rack insert for golf bags, a pair of complementary plates formed with corresponding arrangements of club supporting apertures, a pair of elongated narrow posts between which said plates are interposed and arranged in spaced parallel relation to each other, means rigidly fastening said plates to said posts, and a series of flexible and resilient rods extending between said plates and connected at their ends thereto, there being a plurality of said rods leading from the margin of each of the apertures in said plates.
20. In a club rack insert for golf bags, a pair of complementary plates formed with corresponding arrangements of club supporting apertures, a pair of elongated narrow posts between which said plates are interposed and arranged in spaced parallel relation to each other, means rigidly fastening said plates to said posts, and a series of flexible and resilient rods extending between said plates and connected at their ends thereto, there being a plurality of said rods leading from the margin of each of the apertures in said plates.
25. In a golf bag having a flexible tubular side wall and a bottom wall, a pair of posts extending along the inner face of opposite sides of said side wall, a pair of spaced parallel plates fixed at opposed marginal portions thereof on said posts, said plates having corresponding arrangements of club supporting apertures, and a plurality of rods leading from the margin of each of the apertures in one of said plates to the margin of an opposing aperture in the other of said plates, said rods having their ends engaged in holes formed in said plates to receive them.
30. In a rack insert for golf bags, embodying a plurality of spaced parallel posts, a pair of spaced parallel plates perpendicularly arranged between and fixedly carried by said posts, each of said plates being formed with a series of apertures correspondingly arranged relative to and opposing the apertures of the other plate; the improvement consisting of a series of golf-club-handle guides extending in parallel relation to each other between and secured to said plates, each of said guides leading between opposed apertures in said plates for directing the handle of a golf club inserted through an aperture in one of the plates through the opposing aperture of the other plate.
35. In a rack insert for golf bags, embodying a plurality of spaced parallel posts, a pair of spaced parallel plates perpendicularly arranged between and fixedly carried by said posts, each of said plates being formed with a series of apertures correspondingly arranged relative to and opposing the apertures of the other plate; the improvement consisting of a series of golf-club-handle guides extending in parallel relation to each other between and secured to said plates, each of said guides leading between opposed apertures in said plates for directing the handle of a golf club inserted through an aperture in one of the plates through the opposing aperture of the other plate.
40. In a rack insert for golf bags, embodying a plurality of spaced parallel posts, a pair of spaced parallel plates perpendicularly arranged between and fixedly carried by said posts, each of said plates being formed with a series of apertures correspondingly arranged relative to and opposing the apertures of the other plate; the improvement consisting of a series of golf-club-handle guides extending in parallel relation to each other between and secured to said plates, each of said guides leading between opposed apertures in said plates for directing the handle of a golf club inserted through an aperture in one of the plates through the opposing aperture of the other plate.
45. In a rack insert for golf bags, embodying a plurality of spaced parallel posts, a pair of spaced parallel plates perpendicularly arranged between and fixedly carried by said posts, each of said plates being formed with a series of apertures correspondingly arranged relative to and opposing the apertures of the other plate; the improvement consisting of a series of golf-club-handle guides extending in parallel relation to each other between and secured to said plates, each of said guides leading between opposed apertures in said plates for directing the handle of a golf club inserted through an aperture in one of the plates through the opposing aperture of the other plate.
